UNITED STATES PATENT OFFICE

FRITZ GOSSLAU, OF BERLIN-CHARLOTTENBURG, GERMANY, ASSIGNOR TO SIEMENS & HALSKE, AKTIENGESELLSCHAFT, OF SIEMENSSTADT, NEAR BERLIN, GERMANY, A CORPORATION OF GERMANY

PISTON FOR INTERNAL COMBUSTION ENGINES

Application filed January 6, 1931, Serial No. 506,921, and in Germany August 10, 1929.

My invention relates to internal combustion engines, and more particularly to pistons for internal combustion engines.

The piston head of an internal combustion engine, for example of an aircraft motor, is, as is well known, a part of the engine particularly exposed to high temperatures. It has, therefore, already been suggested to provide a special liquid cooling for the piston head. The danger of the piston head being excessively heated is, thereby, no doubt, lessened but there is also the drawback that the liquid cooling is already effective when the internal combustion engine is being started, and counteracts in an undesirable manner the heating of the piston necessary for the sure starting of the engine.

It is also known to employ for cooling the piston metals fusing easily and having melting points down to 60° C. At the temperatures which the piston is in this case liable to assume, it is not possible to prevent an evaporation of the easily fusing metals so that a considerable pressure is produced in the interior of the piston.

According to my invention these drawbacks are avoided by making at least the piston head of an, in itself already known, improved beryllium-alloy having a very high heat conductivity. This has the effect that, when the engine is being started, the piston becomes warm very quickly and thus facilitates the warming up. Besides this, to subsequently cool the piston, a substance is employed, which is solid under ordinary conditions but changes, at about the temperature the piston assumes when in operation, into the liquid state without evaporating, and only produces a cooling effect when this stage is reached. A salt or salt mixture melting at a sufficiently high temperature, for instance potassium nitrate and lithium nitrate known per se for similar purposes, may be used for cooling the piston head. As a rule, it is sufficient if the melting point of the salt, inserted into the piston, preferably in the form of powder, is about approximately 300° C.

In the accompanying drawing an example is shown for carrying out the invention. In the piston body *a* the bore *b* is, as is known,

provided to take the wrist pin. The piston rings are indicated at *c*. Into the space between the piston head *c* and the wall *d*, a salt mixture *f* is introduced in powder form.

When a combustion motor provided with the illustrated piston is started, the piston head *c* becomes hot, as desired, relatively quickly, as the salt *f*, which is at first still in the form of a solid mass (due to the previous operation of the engine), does not yet perform an independent movement to and fro within the piston chamber, and does not, therefore, practically influence the heating in any way.

When during operation the temperature of the piston head *c* has reached the melting point of the salt *f*, the latter becomes liquid and effects by its splashing a vigorous cooling of the piston head *c*, by increasing considerably the transmission of heat from the piston head through the walls of the piston. The salt liquefied under the influence of the heat, washes, through the movement it makes, the inner side of the piston head and thereby carries away a great part of the heat from the piston head. Besides the piston head, other parts of the piston or the whole of the piston may, if desired, be made of an improved beryllium-alloy.

Particularly suitable are copper-beryllium alloys containing up to 13% of beryllium. Suitable are also nickel-beryllium alloys, cobalt-beryllium alloys as well as iron-beryllium alloys. All the said alloys may contain altogether, up to about 40% of additions of other metals, particularly copper, nickel, aluminum, magnesium, zinc, tin, phosphorus, silicon and carbon. Of the last three elements, in general, additions of only a fraction of a per cent come into consideration. Such beryllium alloys do not naturally possess any such properties as would make them appear particularly suitable for the present purpose. Through a suitable heat treatment, it is, however, possible to increase particularly their hardness and mechanical strength to such a high degree that they become an excellent material for the piston head or for the whole piston.

As a rule, it is advisable to make the piston

head, or the whole piston, of the desired beryllium alloy and then to improve the finished parts by subjecting them to a suitable heat treatment. Such a treatment may consist substantially in cooling the parts quickly from temperatures between approximately 700° to 1200° C., according to the composition of the alloy in question, and in subsequently ageing them artificially at lower temperatures between 250°-500° C.

I claim as my invention:

1. In a piston for internal combustion engines having at least its head made of a heat treated beryllium alloy, a normally solid substance disposed adjacent to said piston head and adapted to liquefy at the normal operating temperatures of the piston and being non-vaporizable at said temperatures, for transferring heat from the piston head of its sides.
2. In a piston for internal combustion engines having at least its head made of a heat treated beryllium alloy, a normally solid salt disposed adjacent to said piston head and adapted to liquefy at the normal operating temperatures of the piston and being non-vaporizable at said temperatures, for transferring heat from the piston head to its sides.
3. A piston for internal combustion engines having at least its head made of a heat treated beryllium alloy, and having a compartment adjacent to its head, partly filled with a normally solid substance adapted to liquefy at the normal operating temperatures of the piston and being non-vaporizable at said temperatures, for transferring heat from the piston head to its sides.
4. A piston for internal combustion engines having at least its head made of a heat treated beryllium alloy, and having a compartment adjacent to its head, partly filled with a normally solid salt adapted to liquefy at the normal operating temperatures of the piston and being non-vaporizable at said temperatures, for transferring heat from the piston head to its sides.

In testimony whereof I affix my signature.
FRITZ GOSSLAU.
